COMBINED COT AND CRIB FOR
AUTOMOBILES

Herbert S. Isaacson, Levittown, N. Y.

Application August 22, 1950, Serial No. 180,731

2 Claims. (Cl. 5—94)

1

This invention relates to a combined cot and crib especially designed for use in automobiles, and which may be folded into a small package for storing in a small place and be easily transported from place to place. The cot is adaptable by change of arrangement to open fully and occupy the space which may be defined as the area between the side doors and between the front and rear seats of the automobile. The height of the cot will be approximately the height of the cushion of the rear seat and the net effect will be equivalent to an extension of the rear seat to rear of the front seat. This arrangement will then permit a number of children to use this extended area for sleeping purposes, etc.

An object of this invention is to provide a convertible cot having end legs and intermediate legs and hinged side frame members with the hinges and intermediate legs positioned in offset relation from the lengthwise mid-portion of the side members to cause the intermediate legs to clear the raised floor portion covering the drive shaft of the automobile.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a top plan view of the convertible cot in fully opened form.

Figure 2 is a side elevation of the cot shown in Figure 1, and showing the application thereto of crib walls.

Figure 3 is an end view of the cot shown in Figures 1 and 2.

Figure 4 is a view of a fragmentary portion of the convertible cot, shown in cross-section, with the canvas covering removed, the section being taken on line 4—4 in Figure 1.

Figure 5 is an end view of the cot, looking in the direction of line 5—5 in Figure 4.

Figure 6 is a cross-section of a fragmentary portion of the cot showing the foldable end portion in upright position.

Figure 7 is an end elevational view of the foldable end section in upright position.

Figure 8 is a top plan view of the upfolded cot shown in Figures 6 and 7.

Figure 9 is a side elevation of the cot as installed in an automobile and showing in dot-an-

2

dash lines the upfolded position of the foldable end portion of the cot, the automobile body being in cross-section taken on line 9—9 in Figure 10.

Figure 10 is a cross-sectional view of the automobile body, the section being taken on line 10—10 in Figure 9 and showing the cot installed therein between the front and rear seats, the cot also having a crib mounted thereon.

Figure 11 is an end view of a fragmentary portion of the cot and crib shown in Figure 10 on an enlarged scale.

Figure 12 is a cross-sectional view taken on line 12—12 in Figure 11.

In the illustrated embodiment of the invention, the numeral 10 indicates a convertible cot comprising a jointed frame 11 and a cover 12 made of flexible fabric.

The frame 11 is of substantially rectangular form and includes an end section 13, a small intermediate section 14 and an end section 15. The end section 13 includes side rails 16 having right-angular hinges 17 pivoted thereto. The hinges 17 are secured to leg members 18, 18 which are pivotally connected at their mid-positions by a rivet 20.

The small intermediate section 14 is pivotally secured to the end section 13 by T-shaped hinges 21. The upright portions 22 of the hinges 21 are secured to leg members 23, 24' which are pivotally connected at their mid-positions by a rigid offset bracket 24 pivotally mounted at 25.

The end section 15 includes side rails 16 having right-angular hinges 17 pivoted thereto. The hinges 17 are secured to leg members 18, 18 which are pivotally connected at their mid-positions by a separable wing nut and bolt 26.

The purpose of the removable wing nut 26 is to permit separation of the legs 18 so that in the upfolded position of the cot 10, the legs may be turned over and lie parallel with the upfolded portion 16 of the side rail (Figures 5 and 6).

The leg member 23 of the intermediate leg assembly is continuous. The leg 23' is a two-section leg. The continuous leg 23 is pivotally connected at its upper end to the T-shaped hinges 21. The two-section leg 23' is made of sections 23² and 23³ which are secured in the offset bracket 24. The pivot 25 of the bracket 24 connects the mid-portion of the bracket to the mid-portion of the continuous leg 23.

The bracket 24 is formed of two plates which are respectively secured to opposite sides of the leg sections 23² and 23³. The leg sections are thereby held in offset relation but in the same transverse plane and parallel to each other. The

plates forming the bracket are flat at the middle and lie on opposite sides of the continuous leg 23. The plates hold the assembled legs in one plane and permit the continuous leg 23 and the two-section leg 23' to swing relative to each other.

The continuous leg member 23 is connected to a hinge 21 by rivets 28 passing therethrough. The upper leg member 23' of the two-section leg 23' is also connected to a hinge 21 by rivets 28 passing therethrough.

The hinges 21 are pivotally connected by pivot pins 30 passing through the side members 16 of the end section 13 and the intermediate section 14 of the frame 11. In straight or upfolded relations, the side members 16, 16 are locked by a transverse pin 31, which is removable when the cot is changed from one use to another use.

It is to be noted that the removable pin 31 on each side of the frame is removed when the cot 10 is folded for storage purposes. The removable pins 31 must normally be used to support the small intermediate section 14 of the jointed frame 11 in downfolded as well as in upfolded positions.

As shown in Figure 1, it will be seen that in the upper face of one rail 16 of the cot 10 are three upright apertures 34. In the upper face of the other rail 16 of the cot 10 are two upright apertures 34' (Figures 2, 10, 11 and 12). Mounted on the cot 10 and secured by the apertures 34 and 34' is a crib 35. The crib has a tiltable side wall 36 having an upper rail 37 and a lower rail 38. The crib has a stationary side wall 40 having an upper rail 41 and a lower rail 42. The lower rail 42 of the non-tiltable side has three downwardly projecting pins 43 fitting in the apertures 34.

Each end of the upper rail 37 is pivotally secured to the body of the crib 35 by a screw 44 and a connecting plate 45 having an elongated slot 46 through which a bolt 47 passes. The connecting plate 45 permits the tiltable side wall 36 to be tilted and locked in the tilted position in relation to the crib 35 by a wing nut 48.

The tiltable side wall 36 permits this wall to be adjusted to an inclined position to suit the contour of the rear face of the front seat of the automobile. This permits a cot of the full distance between the front and rear seats to be used at the seat level. This tiltable side wall also permits the cot when coacting in conjunction with the crib to have side walls in an upright position and yet allow for the incline of the front seat.

When the tiltable side wall 36 is swung to the desired angular position, it is locked to the upper end rails 65 of the end walls of the crib by means of the two slotted arms 45 and bolts 47 and wing nuts 48.

To permit the upfolding of the rail section 15, I provide a specific hinge 50 having the hinge leaves bent into angular shape to permit the hinge leaves to contact both sides of a right-angular corner of a rail 16 on the cot 10, instead of lying on one flat surface as usual. It is to be noted that the left half of the hinge 50 has the same angular form as the right hand half and thus in unfolded position, the right half abuts against the left half, limiting the section 15 to swing to an upright position. The hinge 50 makes it possible to fold the adjoining side rail sections 14 and 15 on a plane passing through a diagonal line of the rail. Two hinges 50 make it possible to fold the cot into the right-angular position shown in Figure 6.

The lower rail 38 of the tiltable side wall 36

has pins 57 extending therefrom at opposite ends. The pins 57 extend into the lower rail 58 of the end walls 56 of the crib. This permits the tilting of the tiltable wall 36. It is to be noted that a support pin 59 is provided in each lower rail 58. The pins 59 extend vertically downwardly into the apertures 34'.

Figure 1 shows grommets 60 positioned in spaced apart relation lengthwise of the cover 12. A similar set of grommets (Figure 9) 61 is positioned in the cover 12 close to the lengthwise bottom edge 62 thereof. Figure 3 shows lock pins 63 extending sideways from one of the rails 13. As shown in Figures 1 and 9, it will be seen that the two sets of grommets 60 and 61 are in linearly aligned relation. At the opposite side of the cot 10 the rail 16 has staples 64 by means of which one lengthwise end of the cover 12 is secured. The object of the double sets of grommets in the cover 12 is for making the cot either narrow or wide for use in automobiles having small or large distances between the front and rear seats. When the set of grommets 61 is used, the cot is fully opened to a width that would accommodate a fully grown normal person.

Figure 6 shows two holding pins 51, 52 in spaced apart relation from each other. A tie rod 53 is pivoted to the end section rail 15 by a pin 54. The other end of the tie rod 53 has a hook shaped end 55. This arrangement makes it possible to connect the tie rod to the pin 51 to secure the right-angular position of the cot shown in Figure 6, or to secure the tie rod to the pin 52 so as to form a reclining back to the cot. In this reclining position the cot may be used as a beach chair.

It will be noted that the upfolding of one end of the cot results in its occupying a fractional part of the width of the automobile and thus permits normal occupancy of the rear seat by one or more persons, while at the same time permitting the occupancy of the shortened cot by one or more children. This change is accomplished without tools, as elements utilized in serving one function are utilized and essential in serving the other function.

As shown in Figure 9, the combined cot and crib 10 is shown installed in an automobile 70 having a raised floor portion 71 covering the drive shaft 72 of the automobile. Figure 9 shows the end leg members 18 and the leg members 23, 23' positioned in offset relation from the longitudinal mid-portion of the combined article. This offset relation causes the leg members 23, 23' to clear the raised floor portion 71 of the automobile 70.

In accordance with the patent statutes I have described and illustrated the preferred embodiment of my invention, but it will be understood that various changes and modifications can be made therein without departing from the spirit of the invention as defined by the appended claims.

I claim:

1. A combined cot and crib for an automobile having a raised longitudinally positioned floor portion, said cot and crib having a body supporting cover member and legs raising said body supporting cover member above said raised floor portion, said combined cot and crib being adapted to be transformed from a fully open cot occupying the full width of the automobile between opposite doors to a partly folded cot adapted for occupying a fractional part of the width of said automobile between said doors to permit normal occupancy of a portion of the rear seat by one

or more persons, said cot comprising hinged end legs and intermediate legs and hinged sectional side frame members with the hinges and intermediate legs positioned in offset relation from the mid-portion of said side frame members, to permit said intermediate legs to clear said raised floor portion covering the drive shaft of said automobile, and further hinges in said side frame members permitting end sections of said side frame members to fold upwardly into angular relation with the stationary side frame members, means to brace said upfolded side frame sections to the portions remaining in horizontal position, the end legs at said upfolded end portion being separably cross connected to permit their separation and folding in parallel relation with said upfolded side frame sections.

2. A combined cot and crib for an automobile having a raised longitudinally positioned floor portion, said cot and crib having a body supporting cover member and legs raising said body supporting cover member above said raised floor portion, said combined cot and crib being adapted to be installed between the tiltable and slidable front seat and fixed rear seat of an automobile, said crib having upper and lower side and end wall rails, one of the crib walls being adjustable to an inclined position to contact the rear surface of said front seat, said adjustable wall being

pivoted to the lower end wall rails of said crib and locked to the upper end wall rails, a cover fixed to one side of said cot and being free at the other side of said cot, said cot having lock pins fixed on said other side, said cover having sets of linearly aligned grommets at said free side to permit said cover to be adjustably secured to said lock pins to vary the width of said cot between the front and rear seats of an automobile to suit the adjusted distance between said seats, said adjustable crib wall when inclined to contact the rear surface of said front seat preventing said cot and crib from moving around between said front and rear seats and damaging the upholstery of said automobile.

HERBERT S. ISAACSON.
